UNITED STATES PATENT OFFICE

2,538,256

COMPUTING SCALE

Otto Malcher, Chicago, Ill.

Application January 25, 1949, Serial No. 72,970

14 Claims. (Cl. 235—61)

1

This invention relates in general to a computing mechanism for indicating and registering values, particularly as used in a computing scale mechanism and is more particularly described as an improvement and simplification of certain of the indicating and registering mechanism as disclosed in my computing scale Patent No. 2,397,970, of April 6, 1946, and is a continuation in part of my application Serial No. 596,299, filed May 28, 1945, now abandoned.

In the prior patent, the indicating and recording values are obtained from a ratchet disc of large diameter having one hundred teeth corresponding to tens graduations and therefore having a considerable momentum requiring an accurate and efficient clutch mechanism to insure that there is no slippage or lost motion which seriously interferes with any computation of values in a machine of this kind.

An important object of the present invention is in the provision of an improved and simplified mechanism reduced in size, and particularly in the diameter of the operating parts to reduce their momentum; to provide a mechanism which may be bodily inserted and substituted for a corresponding part of the mechanism as disclosed in my Patent No. 2,397,970 for effecting a similar and improved operation thereof.

A still further object of the invention is in the provision of a computing device having separate parts for hundreds, tens, and units graduations, with means depending upon the movement of the hundreds part for positioning the part having the tens graduation, and means controlled by the position of the part having the tens graduations for positioning the units graduations.

A further object of the present invention is in the provision of a computing device having separate parts for units, tens, and hundreds graduations with means for positioning the part containing the hundreds graduation, in subsequently operating the parts having the tens and units graduations and in aligning the parts and their indicating numerals into full hundreds, tens, and units graduations.

A still further object of the invention is in the provision of a computing device for registering values having separate parts for hundreds, tens, and units graduations, locking the tens and hundreds parts together by moving the tens part, and setting up the unit part in accordance with the movement of the tens part.

Other and further objects of the invention will appear in the specification and will be ap-

2

parent from the accompanying drawings, in which

Fig. 1 is a side elevation of a mechanism in accordance with this invention;

Fig. 2 is an edge elevation of parts of the mechanism shown in Fig. 1;

Fig. 3 and Fig. 4 are fragmentary side elevations of some of the parts shown in Fig. 1, and associated operating parts; and,

Fig. 5 is an enlarged detail of the clutch mechanism.

A part of the mechanism shown in the drawings is designed and intended to be bodily inserted and substituted for a portion of the indicating and registering mechanism which is found in my patent above referred to, the calculated product of two values being set up as described in that patent and the parts having the hundreds and tens graduations, and the notched wheel controlling the units graduations all being fastened together and being flexibly connected to and moving with an arm 375 as shown herein and in the said patent.

Referring more particularly to the mechanism shown in the drawings, a shaft 332 corresponds to the money value shaft of the same number as set forth in my prior application in which the numerical product of two variables sets up a projecting arm 375, which is secured to the shaft, in different angular or rotated positions depending upon the set value or product. Rotation of the shaft 332 causes rotation of the arm 375 which is held by a spring 374 in engagement with a stop 377 attached to a hundreds wheel or disc 401 free to rotate on the shaft 332 thereby driving the wheel or disc to any position as determined by the value set up rotation of the shaft. The periphery of the disc 401 is spiral in form having nine shoulder reductions 402 and one large shoulder 403 to provide for contact engagement of a visible hundreds indicating numeral device 404.

The hundreds disc stop 377 is located at one side of the value set up arm 375 to which it is connected for limited separation movement by the spring 374 and firmly attached to the hub of the hundreds wheel and movable therewith are two ratchet discs 405 and 205 with the teeth thereof extending respectively in opposite directions.

A tens segment 407 is freely pivoted on the shaft 332 and has ten stepped teeth 408 in its outer edge between radial lines which define the sector of space between two adjacent shoulders 502 of the hundreds wheel or disc 401. Also se-

cured to or formed integrally with and extending oppositely from the segment 407 is an arm 411 having a curved outer edge 412 in which are teeth 413.

To operate the segment 407, a lever 425 is mounted upon an intermediate fixed pivot 423 and has a slot 426 at one end engaging a pin 427 projecting from the arm 411 of segment 407 near its mounting shaft 332 but opposite the toothed portion 408. The other end of this lever 425 has a projection 428 which is pressed against a cam H on a cam shaft 17 by a spring 429, thus tending to rotate the segment in the same direction as the disc 401 by means of the lever 425. This movement positions the teeth 408 of the tens segment in accordance with the position of the hundreds disc and also positions the curved edge 412 of the tens segment for controlling the units indicating device as next described.

The tens segment 407 has two attached spring pressed dogs 417 and 217 mounted on the same pivot 408 supported by arm 411 of the segment 407, one adapted to engage the teeth of disc 405 and the other to engage the opposite teeth of disc 205 respectively. Springs 216 each connected to one dog and to the arm 411 tend to hold the dogs in engagement with teeth 405 and 205. Both dogs are held out of their disc engaging positions by the contact of a flange 421 on the extremity of a bell crank 232 rotatable on the intermediate fixed pivot 423 and its other end held against a cam G on cam shaft 17 by a spring 422. When the tens segment is moved by lever 425 in a counter-clockwise direction until its dog 417 engages a tooth of its ratchet disc 405, the other dog will at the same time engage a tooth 205 of its ratchet disc thereby locking the arm 411 and the tens segment 407 in connection with the hundreds disc 401 for movement together in both directions.

This movement of the tens segment will never be more than one-tenth of a complete rotation because each of the discs 405 and 205 have ten teeth, and therefore the teeth in the outer edge of the segment need not be any more than ten or twelve in number and need not extend entirely around the periphery of a wheel as in my previous case referred to above.

The units setting and indicating mechanism may be of any desired or suitable construction or substantially the same as that shown in Fig. 11 of my application cited above, a part of which is reproduced in Fig. 1 of the present application to show the general construction and operation of the parts. In order to lock disc 401 and segment 407 together in their value indicating positions, a locking clutch for tightly gripping the curved outer edge 412 is mounted at the end of a bar 104 pivoted at its upper end on shaft 332 and extended beyond or below the curved edge 412 of the arm 411 and carrying at its lower end jaws 105, 106 at opposite sides of the curved edge which are operated toward and from engaging position by meshing gears 107, one of which is actuated by an attached projecting lever arm 108 normally drawn into clutching position by a spring 109 attached at one end to the arm 108 and the other end attached to a fixed projection on the frame (not shown).

This lever is controlled by an actuating lever 111 in the form of a bell crank mounted at an angle upon a shaft 112 in the machine frame and having one arm extending over the lever arm 108, and its other arm having a projection 113 engaging a clutch controlling cam M on shaft 17.

The timing of this cam is such that as soon as the machine is started for a new value, the pro-

jection 113 of the operating lever 111 is actuated by the cam to move the other arm and press the clutch arm 104 against the tension of spring 109 in a direction to release the clutch jaws from engagement with the curved edge 412. The clutch is not released to allow its application by the spring 109 until the cycle of operation is nearly complete.

As the segment 407 is conveniently graduated in ten teeth or steps 408, a positive stop is provided comprising a movable stop bar 115 mounted in suitable guides 116. At its end is a tooth 117 for engaging any one of the teeth 413. A spring 118 attached at one end to a projection 119 on the bar and at the other end to a fixed projection 120 on one of the guides 116 urges the stop bar into engagement with teeth 413. At the other end of the bar is a pin or projection 121 for engaging one of the guides 116 to limit the movement of the stop bar in tooth engaging position.

To control the stop bar 115, a lever 122 is mounted intermediate its ends upon a fixed pivot 123 and has the edge of one extremity 124 in engagement with the projection 119 on the stop bar. At the other end of the lever is a contact member 125 for engaging the tens cam K secured to the cam shaft 17. The surface of this cam has a notch which actuates the lever 122 to withdraw the stop bar from its engaging position as soon as the mechanism is started for a calculation and to hold the stop bar out of such engagement until its reengagement.

It may happen that the calculated value is an exact multiple of ten, that the dog 217 and 417 will exactly engage their corresponding teeth of discs 205 and 405 without reverse movement of segment 407, but if there are any variations of the units values, the operating movement of the segment 407 until the dogs 217 and 417 are engaged and locked together with the teeth of discs 205 and 405, and the backward or truing back movement of segment 407 until the stop tooth 117 engages the next lower tooth 413 causes a proportional reverse movement which sets up the proper unit on the units value wheels.

This units value movement is effected by an arm 126 pivoted at its upper end on shaft 332 and having a rack 128 at its lower end in engagement with a pinion 129 secured to a relatively fixed shaft 130 suitably mounted in the machine frame. A spring 131 is connected at one end to the arm 126 and at the other end to a fixed bar of the machine frame, which tends to move the arm about the shaft 332 in a direction opposed to the value setting up directional movement of the tens segment 407 by its arm 425, which happens to be a clockwise direction as viewed in Fig. 1.

Attached near the lower end of arm 126 upon a pivot 132 is a lever 133 having a notch 134 engaged by a projection 135 at the bottom of the clutch supporting bar 104, and the lever having a toothed extremity 136 for engaging the projection 135 if it becomes released from the notch 134. At the other end of the lever 133 is a knock-out projection 137 which is engaged as hereinafter set forth for disconnecting the arm 126 from the clutch bar 104 with which it moves as a unit under ordinary conditions. A spring 143 attached at one end to the holding lever 133 and at the other end to the units movement arm tends to hold the lever with its notch 134 in engagement with the clutch bar projection 135.

Attached by a rivet 437 and projecting from the lower end of the arm 126 is an operating bar 138

having a projection at its outer or free end adapted to engage the surface of a controlling cam I secured to the cam shaft 17 for operating the arm 126 and pressed against the cam by the spring 131.

Secured to a sleeve 167 rotatable on shaft 130 is a units value stepped wheel 140, the shaft being rotated by the rack 128 at the lower end of arm 126 and a pinion 129 secured to the shaft, in accordance with the backward movement of the arm as determined by the engagement of the stop tooth 117 with the teeth 413 on the arm 411 of the tens segment 407. On this units stepped wheel 140 are high points 141 and 156 at the extremities thereof for indicating zero values, and graduated steps therebetween for indicating units values from one to nine. A second zero projection 418 is required on the segment 407 in registering any value over 9½ units. The second zero is already in position and shifting of the reading line brings the next full tens line into view instead of 9 and some fraction thereof.

For the present, the sleeve 167 may be regarded as rotatable with the shaft 130, but there is a flexible connection between them consisting of an arm 168 extending from the units wheel 140 having a pivot 169 at its outer end to which one end of a link 170 is connected, this link having a broad but somewhat pointed notch 171 in its edge for engaging the pointed extremity of an arm 172 rigidly secured to the shaft 130. A spring 173 connected at one end to the outer end of the link 170 and at the other end to a fixed point 174 on the units wheel 140 tends to hold the projection 172 centered in the notch 171.

When the lower end of arm 126 is moved until the stop tooth 117 engages the next tooth 413 in its truing back direction, the shaft 130 is moved and the units wheel 140 is accordingly set with this truing back movement. For example, if the stop tooth 117 exactly engages one of the teeth 413 after the segment 407 has been advanced by its operating arm 425, an even multiple of ten has been set up and no truing back movement of the segment will be required, but if some intermediate units value such as 827 has been set up, the segment 407 will be moved past the tens tooth indicating 820 and seven-tenths of the amount for the next tooth. This backward movement sets up the units value wheel 140 for its seventh graduation which operates the units value wheels as hereinafter described.

After the units value is set up by the operation of the arm 126 and the units wheel 140, the arm 126 is retained in its set up position and a short time after the next calculation, it is returned by the engagement of its arm 428 with the corresponding cam I on the cam shaft 17 and this movement also returns the units wheel 140 to its zero position as indicated in Fig. 1.

A units operating bar 144 has guide slots 145 engaged by fixed projections 142 and has a projecting extremity 145 at its lower end for engaging the zero high points 141 and 156 and the intermediate unit value stops of the units wheel 140. Near the upper end of this bar 144 is a rack 146 engaging a pinion 147 secured to a units value wheel 149 freely mounted upon a shaft 148, the wheel having an outer marginal surface upon which the units values appear in large numerals.

A tens value wheel 150 has an outer marginal surface upon which numerical units appear in large size corresponding with those of a units wheel 149. This tens value wheel may be mount-

ed freely upon the same shaft 148 as that upon which the units wheel 149 is rotatably mounted, and at the hub it is provided with a gear 154 engaging a rack 155 at the upper end of an operating bar 151 having a projecting arm 156 and moved in timed relation to engage one of the teeth 408 of the segment 407, thereby setting up the tens value in accordance with the segment tooth engaged.

Similarly a hundreds value wheel 157 is mounted upon the shaft 148 and has an outer marginal surface upon which the units numerals appear in large size corresponding to the other two numeral wheels. At the hub of this wheel 157 is a gear 159 engaged by a rack 160 at the upper end of an operating bar 161 having an extending arm 162 and operated in timed relation to the units and tens wheels to set up a value on wheel 157 depending for movement upon the engagement of an arm projecting therefrom (like the tens arm 156) with one of the shoulders of the hundreds disc 401 depending upon the position of the disc.

A suitable mechanism for moving the units, tens, and hundreds wheels and their corresponding operating bars 144, 151, and 161 comprises coil springs 181 each connected at one end to a projection of one of the operating bars and at the other end to a fixed bar 182 of the machine. These springs tend to move the bars downwardly until the units bar extension 145 engages the units stepped wheel 140, the tens bar arm engages the tens segment 407, and the hundreds bar arm 162 engaging the hundreds disc 401. These positioning parts having been set to indicate values, the downward movement of the bars causes a corresponding movement of the number wheels 149, 150 and 157 to indicate the calculated value at the reading line. To set the number wheels at zero, a cross bar 183 is mounted at the extremities of arms 184 of bell cranks mounted on shaft 422, and each bell crank having another arm 185 with a projection 186 near the end for engaging similar cams L mounted on and rotatable with the timing shaft 17.

The bar 183 is raised and lowered by the operation of the cams L to engage lower contact ends of the bars 144, 151 and 161 against the pressure of springs 181, and the cams each have a low place to permit the bar 183 to drop below the wheel operating bars 144, 151 and 161 to set up any calculated values. As soon as the machine is actuated for the next calculation, the cams L raise the bar 183 and with it the wheel operating bars setting all the number wheels at zero indication.

The arrangement of the parts is such that when the value set up arm 375 is moved to any calculated value by its shaft 382, it carries with it the stop 377 on the hundreds disc 401 flexibly connected by spring 374. Thereafter the tens segment 407 is driven in the same direction by its operating lever 425 controlled by its timing cam H and spring 428 to engage the ratchet discs 295 and 405 and is locked in engagement therewith so that the hundreds disc and the tens segment are thereafter operated together in both directions of rotation. The unit value which has been set up in the hundreds disc by the position of the value set up arm 375 and by the position of the tens segment is amplified in the position of the head 412.

If the set up value is an even ten, one of the teeth 413 of the head 412 will exactly engage the tooth 117 so that there will be no backward or

reverse movement of the head 412. If it is necessary to move this head rearwardly any portion of the length of one of the teeth before the stop tooth 117 is engaged, this proportion of movement of the head 412 sets up the corresponding units value. The clutch mechanism as shown in Fig. 5 is operated in timed relation to engage the head 412 and to move with it the proportion of movement of one of the teeth 413 to register the units values which in turn allows spring 131 of arm 128 to be moved thereby and correspondingly moving the units wheel 140 as above explained.

The operating bars 144, 151 and 161 are then moved to acuate their corresponding units, tens and hundreds wheels setting up the calculated value in a reading line having numerals of large size.

It is necessary to make provision for the condition which arises when more than nine and one-half units are set up on the units wheel 140, thereby requiring a change to the next full tens valuation. A knock-out projection 196 is provided which engages knock-out projection 137 of dog 133. In this knock-out position, a second zero projection 156 forming a part of the units wheel 140 will be located below the units operating bar 145 which communicates the units movement to the units indicating wheel 140 which corresponds with the tens and hundreds indicators located at the reading line.

Engagement of the knock-out projection 196 releases tooth 135 from its engagement with the tooth 134 with which it is in contact, which allows the hundreds wheel 401 and the tens segment to be driven together by spring 374 until the stop 377 again engages the arm 375 in its fixed position from which it was separated in the reverse rotational movement, whereby the next higher tens graduation will be restored, the units character being determined by the second zero projection 156, then under the extremity 145 of the indicator operating arm 144.

After the calculated value is set up by the numeral or indicating wheel, the set values may be indicated simply by the numbers, and therefore visible to a customer, or the number mechanism may be repeated so that both the customer and the operator may see it on different sides of the machine, or the set value may be printed upon a ticket which is furnished to a customer. The actual value setting up mechanism is shown more clearly in Figs. 1 and 2, or any similar or equivalent means which may be of any well known or suitable type.

In attempting to grip a comparatively large value set up wheel and to hold it in a rigid fixed position by means of a clutch mechanism, much difficulty is encountered. After the mechanism has been in use for a short time, a slight give or slippage of the clutch mechanism will make all valuations inaccurate so that the operation of the machine is questionable. The present invention simplifies this feature of my invention above referred to and is intended to provide a positively operated and much more reliable clutch since it is applied at a position near the center of movement of the parts and actually operates upon moving parts of so much less weight as compared with the large wheel structures of my application above referred to that there is a greater factor of safety and less likelihood of error.

In a machine of this kind, the calculation must be made and completed in 2½ to 3 seconds in order to be considered commercially successful.

The above construction does away with about nine-tenths of the weight of the tens and hundreds wheels as compared with my application above referred to which materially reduces the inertia produced by such masses.

In this form of the invention, greater accuracy of calculation is possible with operating wheels, discs, and parts of smaller sizes. The calculated or set up value is given to a hundreds wheel or a disc having tens graduations for its entire circumference, and a tens segment having only tens graduations is positioned thereby and locked thereto. The units value as set up in the hundreds wheel or disc and by it applied and magnified in the tens segment is spread over a comparatively large surface which makes it possible to position more accurately the set up units value, all valuations depending upon the position of the hundreds wheel.

20 I claim:

1. In a computing device for indicating numerical values, separate parts for hundreds, tens, and units graduations; means for setting up a numerical value dependent upon the position of the hundreds part, means controlled by the value set up in the hundreds part for positioning the tens part, and means controlled by the tens part for positioning the units part, the units part comprising a segment having a single set of ten digit graduations.

2. A computing device, comprising separate movable parts for indicating hundreds, tens and units; means dependent upon the movement of the hundreds part between its positions indicating full hundreds graduations for controlling the movement of the tens part in accordance with the partial movements of the hundreds part, and means dependent upon the movement of the tens part between its full tens graduations for controlling the movement of the units part, the units part having a single set of ten digit graduations for all of the tens graduations.

3. In a computing device for numbers representing values, comprising separate parts having hundreds, tens, and units graduations, operating means for moving the part having hundreds graduations into different relative positions for different values; and means for subsequently operating the part having the tens graduations in accordance with the position of the hundreds part and the part having the units graduations in accordance with the position of the tens part, the units part having ten graduated steps and movable relatively to each of the tens graduations.

4. In a computing device for numbers indicating values and comprising separate parts having hundreds, tens, and units graduations; means for driving the part having the hundreds graduation to different positions indicating values which comprise units, tens, and hundreds; means for moving the tens part to a position determined by a position of the hundreds part, and means for moving the units part to a position determined by the relative position of the tens part, the units part comprising a segment having only ten units steps and movable relatively to any one of the tens graduations.

5. In a computing device for indicating numerical values, comprising separate parts having hundreds, tens, and units graduations, means for driving the hundreds part to a stop position in one direction including units, tens and hundreds values, means for moving the tens part in the same direction as the hundreds part, until it is

stopped thereby, means for locking the tens and hundreds parts for movement together, means for reversing the movement of the tens and hundreds parts to the last full tens graduation, and means dependent upon the amount of said reversing movement for positioning the units part, the units part comprising a segment with only one series of ten steps and movable relatively to any one of the tens graduations.

6. A computing device for indicating numerical values, comprising separate parts having hundreds, tens, and units graduations, means for positioning the part having hundreds graduations to indicate a numerical value in accordance therewith, means controlled by the position of the hundreds part for positioning the tens part, and means controlled by the tens part for separately positioning the units part in accordance with the positions of the tens and hundreds parts, the units part comprising a segment with only one series of ten unit steps.

7. A computing device for indicating numerical values, comprising separate parts having hundreds, tens, and units graduations, means for moving the part having hundreds graduations to different positions depending upon different numerical values, means controlled by the movement of the hundreds part for engaging the tens part and locking it for movement in either direction therewith, and means controlled by the proportional movement of the tens part between its full tens graduations for relatively moving the units part, the units part having one series of ten unit steps.

8. In a computing device for indicating numerical values, separate parts having hundreds, tens, and units graduations; means for driving the hundreds part in one direction to relative positions indicating different values, a flexible connection between the driving means and the hundreds part to permit a limited movement in the reverse direction, means for positioning the tens part in accordance with the extent of movement of the hundreds part, means depending upon the relative movement of the tens part between full tens values for positioning the units part, the units part having only one series of ten units steps, and numerical indicating wheels depending upon the positions of the units, tens, and hundreds part for indicating a numerical value which is originally set up by the position of the hundreds part.

9. In a computing device for indicating numerical values, comprising separate parts having hundreds, tens, and units graduations; means for driving the hundreds part to a value indicating stop position in one direction, a flexible connection between the means and said part, means dependent upon the extent of movement of the hundreds part for moving the tens part in the same direction, means for locking the tens and hundreds parts together, means for reversing the movement of the locked tens and hundreds parts to the last full tens graduation, said reversing movement setting up a graduation of the units part in accordance with said movement and as determined by the positions of the tens and hundreds parts, the units part comprising one series of ten unit steps.

10. In a computing device, comprising separate parts having hundreds, tens, and units graduations, means for moving the hundreds part to a stop position for indicating a numerical value, means for driving the tens part to engage the hundreds part, means for moving the units part

5

in accordance with the extent of movement of the tens part, the units part having a segment with a series of ten unit steps, the step at one end indicating zero, and the segment having a projection forming an additional zero position at the other end thereof, and knock-out means in connection with the segment for moving it to indicate zero when the segment is moved to register more than nine and one-half units.

10

11. A computing device for indicating numerical values, comprising parts having hundreds, tens, and units graduations, means for moving the part having hundreds graduations to a position for indicating a numerical value, means controlled by the position of the hundreds part for also positioning the tens part, means controlled by the tens part for positioning the units part in accordance with the numerical value set up in the hundreds part and the tens part, the units part having one series of ten unit steps movable relative to each tens graduation, and numerical indicating wheels and operating means for each wheel engageable with the hundreds, tens, and units graduations to set up different values in the wheels.

20

12. A computing device for indicating numerical values, comprising separate parts having graduations representing hundreds, tens, and units, means for positioning the part having hundreds graduations to indicate a numerical value in accordance therewith, means controlled by the position of the hundreds part for positioning the tens part, means controlled by the tens part for positioning the units part in accordance with the positions of the tens and hundreds parts, the units part having only one series of ten unit steps movable relative to any tens graduation, numerical indicating wheels for hundreds, tens, and units values, rack members movably mounted for actuating each of the wheels separately, and each of the rack members having a projection for engaging corresponding graduations of the hundreds, tens, and units parts for positioning the wheels to indicate a numerical value depending upon the position of the hundreds part.

30

13. In a computing device for indicating numerical values, separate movable parts for hundreds, tens, and units graduations; means for setting up a numerical value in the hundreds part dependent upon the position thereof, means controlled by the value set up in the hundreds part for positioning the tens part, means controlled by the tens part for positioning the units part, the units part having one series only of ten unit steps movable relative to any tens graduation, a numerical indicating wheel for hundreds, tens, and units graduations, means including rack bars for moving each of the wheels separately, each rack bar having a projection for engaging the graduation of its respective part, and means for moving the rack members so that the projection thereof engage the graduations of their respective parts for moving the wheels in accordance with the numerical value set up by the positions of the hundreds, tens and units parts.

40

14. In a computing device for indicating numerical values, separate movable parts for hundreds, tens and units graduations; means for driving the hundreds part to indicate a numerical value in accordance with the position thereof, means for securing the tens part to the hundreds part for movement together in both directions, means for gripping the tens part and moving it reversely a proportionate part of one grad-

75

11

uation to indicate units, means for magnifying the movement of the units part in accordance with the reverse movement of the tens part, the units part having one series only of ten unit steps and movable relative to any tens graduation, separate number wheels corresponding to the hundreds, tens, and units parts, means including rack bars for rotating the wheels separately, each of the rack bars having a projection for engaging its corresponding hundreds, tens, or units part, and means for moving the rack bars to free the projections thereof from engagement with the graduations of their corresponding movable parts

12

until said parts are positioned to indicate a numerical value.

OTTO MALCHER.
